UNITED STATES PATENT OFFICE.

GEORGE P. WIGGINTON, OF KALAMAZOO, MICHIGAN, ASSIGNOR TO KALAMAZOO LOOSE LEAF BINDER COMPANY, OF KALAMAZOO, MICHIGAN.

BINDER.

1,410,783.

Specification of Letters Patent. Patented Mar. 28, 1922.

Application filed June 23, 1919. Serial No. 306,122.

To all whom it may concern:

Be it known that I, GEORGE P. WIGGINTON, a citizen of the United States, residing at city and county of Kalamazoo, State of 5 Michigan, have invented certain new and useful Improvements in Binders, of which the following is a specification.

This invention relates to improvements in temporary binders or loose sheet holders.

10 The main objects of this invention are:

First, to provide an improved temporary binder or loose sheet holder which is well adapted for use in holding loose sheets and circulars such as those of a loose leaf catalog in which all of the sheets are securely bound when it is desired to handle them in a binder in a bound relation, and at the same time they are readily freed as occasion may require.

20 Second, to provide a loose sheet holder or temporary binder which is compact in structure, light in weight so that it may be easily carried about and at the same time one in which the sheets are bound in a neat and secure manner.

25 Further objects and objects relating to structural details will definitely appear from the detailed description to follow.

I accomplish the objects of my invention 30 by the devices and means described in the following specification. The invention is clearly defined and pointed out in the claims.

A structure which is a preferred embodiment of my invention is clearly illustrated 35 in the accompanying drawing forming a part of this specification, in which:

Fig. I is a rear perspective view of one embodiment of my invention.

40 Fig. II is a detail longitudinal section thereof on lines corresponding to line 2—2 of Figs. III, IV and VII.

Fig. III is a detail transverse section on a line corresponding to 3—3 of Fig. IV.

45 Fig. IV is a detail section on a line corresponding to 4—4 of Figs. II and III.

Fig. V is a detail section similar to that of Fig. II illustrating the expansion of the binder.

50 Fig. VI is a perspective view of sheet body and post bars removed as a unit from the binder members.

Fig. VII is a detail inside view of one of the covers showing the adjusting means for

the binding strips of the embodiment illustrated in Figs. I to VII.

55 Fig. VIII is a detail section on a line corresponding to 8—8 of Fig. IX showing the adaptation of my improvements to the sectional post type of binder.

Fig. IX is a detail section on a line corresponding to line 9—9 of Fig. VIII.

In the drawing similar reference characters refer to similar parts throughout the several views, and the sectional views are taken looking in the direction of the little 65 arrows at the ends of the section lines.

Referring to the drawing, the covers 1 are provided with recesses or chambers. The ends of the flexible back 3 telescope into these chambers; cover 2 also contains the adjusting mechanism designated generally by the numeral 4—see Figs. II and VII. The binding strips 5 are connected at one end to this adjusting mechanism which is substantially that shown in Letters Patent No. 75 1,010,556 issued to me December 5, 1911. As the details of this adjusting mechanism form no part of my present invention, they are not further illustrated or described herein.

The binding strips 5 extend between the 80 covers, being disposed through the clamping members 6 which are pivotally mounted on the covers, these clamping members being mounted substantially as shown in my said patent. The sheets 7 are provided with 85 notches 8 and with holes 9, the notches opening at the binding edges of the sheets and the holes being disposed adjacent the binding edges of sheets. The notches are in

position to receive the binding strips 5 while the holes receive the posts 10 carried by the post bars 11, each bar in the structure illustrated being provided with a pair of the posts. The posts of the bars are disposed

out of alignment so that they over-lap in the 95 sheet body as shown in Fig. III. These post bars are detachably mounted on the clamping members, the bars being provided with pins 12 which engage holes 13 provided therefor in the clamping members. The post 100 bars 11 are provided with notches 11' adapted to register with the notches 8 of the sheets to receive the binding members.

With this arrangement of parts, when the clamping members are separated or retracted, the body of sheets bound by the

posts and post bars may be removed from the binder as a unit as shown in Fig. VI.

In the adaptation of my invention shown in Figs. VIII and IX to a binder of a sectional post type, the binder members consisting of covers and clamping members designated generally by numeral 14 are detachably and adjustably connected by the sectional post binding members 15 which serve 10 in the main the purpose or function of the flexible strip form of binding members of my embodiment shown in Figs. I to VII. The post members 11 are in this embodiment of Figs. VIII and IX the same as in the 15 embodiment described except as to the shape of the notches 11' which are rounded to fit the posts 15.

My improved binder is particularly well adapted for use as catalog binder or the like 20 where it is desirable to provide a comparatively light, simple binder, and at the same time, one in which the sheets are securely held or bound and further, one which permits their rapid removal and replacement as 25 occasion requires.

I have illustrated and described my improvements in two forms or adaptations thereof. I do not illustrate other forms and adaptations which I contemplate as I believe 30 the disclosure made will enable those skilled in the art to embody or adapt the same as particular requirements may render most desirable.

Having thus described my invention, what 35 I claim as new and desire to secure by Letters Patent is:

1. In a temporary binder, the combination 40 with sheets provided with open notches in their binding edges and with holes adapted to receive posts, of covers, clamping members pivotally connected to said covers, and having holes therein, binding strips extending between said covers and adapted to engage said notches of said sheets, said binding strips being arranged through said clamping members and provided with adjusting means, post bars notched to receive said binding strips and provided with pins engaging said holes in said clamping members 45 whereby said post bars are removably retained thereon, and binding posts on said post bars disposed out of alignment to engage said holes in said sheets.

2. In a temporary binder, the combination 50 with sheets provided with open notches in their binding edges and with holes adapted to receive posts, of covers, clamping members pivotally connected to said covers, and having holes therein, binding strips extending between said clamping members, post bars notched to receive said binding strips and provided with pins engaging said holes in said clamping members whereby said post bars are removably retained thereon, and 55 binding posts on said post bars disposed out

of alignment to engage said holes in said sheets.

3. In a temporary binder, the combination 70 with sheets provided with open notches in their binding edges and with holes adapted to receive posts, of covers, clamping members pivotally connected to said covers, binding strips extending between said clamping members and adapted to engage said notches of said sheets, post bars notched to receive 75 said binding strips and detachably engaged with clamping members, and binding posts on said post bars disposed out of alignment to engage said holes in said sheets.

4. In a temporary binder, the combination 80 with sheets provided with open notches in their binding edges and with holes adapted to receive posts, of covers, clamping members pivotally connected to said covers, binding strips extending between said clamping members and adapted to engage said notches in said sheets, post bars notched to receive 85 said binding strips and detachably engage with clamping members, and binding posts on said post bars.

5. In a temporary binder, the combination 90 with sheets provided with open notches in their binding edges and with holes adapted to receive binding posts, of binder members, binding members for said binder members, post bars provided with posts disposed out of alignment to engage said holes in said sheets, said post bars being notched to receive said binding members and removably mounted on said binder members so that 95 when the binder members are separated the sheet body and post bars may be removed therefrom as a unit.

6. In a temporary binder, the combination 100 with sheets provided with holes adapted to receive binding posts, of binder members, binding members for said binder members, post bars provided with posts disposed out of alignment to engage said holes in said sheets, said post bars being removably mounted on said binder members so that 105 when the binder members are separated the sheet body and post bars may be removed therefrom as a unit.

7. In a temporary binder, the combination 110 with sheets provided with holes adapted to receive binding posts, of binder members, a binding member extending between said binder members, post bars provided with posts engaging said holes in said sheets, said post bars being removably mounted on said binder members so that when the binder members are separated the post bars and sheet body may be removed therefrom as a unit.

8. In a temporary binder, the combination 115 of covers, clamping members pivotally connected to said covers, and having holes therein, binding strips extending between said covers, said binding strips being arranged through clamping members and provided 120

with adjusting means, post bars notched to receive said binding strips and provided with pins engaging said holes in said clamping members whereby said post bars are removably retained thereon, and sheet engaging posts on said post bars disposed out of alignment.

9. In a temporary binder, the combination of covers, clamping members pivotally connected to said covers, and having holes therein, binding strips extending between said clamping members, post bars notched to receive said binding strips and provided with pins engaging said holes in said clamping members whereby said post bars are removably retained thereon, and sheet engaging posts on said post bars.

10. In a temporary binder, the combination of covers, clamping members pivotally connected to said covers, binding strips extending between said clamping members, post bars provided with sheets engaging posts disposed out of alignment, said bars being notched to receive said binding strips and provided with means engaging said clamping members whereby said post bars are removably retained thereon.

11. In a temporary binder, the combination of covers, clamping members pivotally connected to said covers, binding strips extending between said clamping members, post bars provided with sheets engaging posts, said bars being provided with means engaging said clamping members whereby said post bars are removably retained thereon.

12. In a temporary binder, the combination of binder members, binding members for said binder members, and post bars provided with sheet engaging posts disposed out of alignment and detachably engaged with said binder members.

13. In a temporary binder, the combination of binder members, binding members

for said binder members, and post bars provided with sheet engaging posts and detachably mounted on said binder members.

14. In a loose leaf binder, the combination with hinged cover portions, of a pair of detachable transfer bars normally lying adjacent to the respective cover members and each having impaling posts thereon adapted to extend through the leaves.

15. In a loose leaf binder, the combination with hinged cover portions, of a pair of detachable transfer bars normally lying adjacent to the respective cover members and each having impaling posts thereon adapted to extend through the leaves and means for securing the cover members together.

16. In a loose leaf binder, the combination with hinged cover portions, of a pair of detachable transfer bars normally lying adjacent to the respective cover members and each having impaling posts thereon adapted to extend through the leaves, and means independent of the impaling posts for securing the cover members together.

17. In a loose leaf binder, the combination with hinged cover portions, of a pair of detachable transfer bars normally lying adjacent to the respective cover members and each having impaling posts thereon adapted to extend through the leaves, and means for securing the cover members and transfer bars together.

18. In a loose leaf binder the combination with hinged cover portions, of a pair of detachable transfer bars normally lying adjacent to the respective cover members and each having impaling posts thereon adapted to extend through the leaves, and means independent of the impaling posts for securing the cover members and transfer bars together.

In witness whereof, I have hereunto set my hand and seal.

GEORGE P. WIGGINTON. [L.S.]
